GEORGE E. NEUBERTH, OF NEWARK, NEW JERSEY, ASSIGNOR TO PIPE & TUBE BENDING CORPORATION OF AMERICA, OF NEWARK, NEW JERSEY, A CORPORATION OF NEW JERSEY

METHOD OF MAKING RINGS FROM TUBING

Application filed October 31, 1927. Serial No. 229,888.

This invention relates to an improved method of cutting rings from tubular material, and is designed particularly for cutting copper or other soft-metal rings used as bushings in the securing of tubes to boiler heads. The method is adapted however, for making rings from tubing for other useful purposes.

The tube which is to be cut into lengths is secured in a die and is spread at one end so as to present a shoulder. The tube is then subjected to a shearing action at the point where the shoulder is and the tube severed at this point. The severed ring can be compressed longitudinally to shape its ends if this step is deemed desirable.

The invention will be more clearly understood from an inspection of the accompanying drawings, in which Fig. 1 is a section of a tube supported in a die, Fig. 2 is a similar view with the tube expanded for a portion of its length, Fig. 3 is a section showing the expanded tube cut by a cutter, Fig. 4 is a view on a reduced scale of the ring after it is cut from the tube, and Figs. 5 and 6 are sections of a part of a modified form of die.

In the drawings the tube is shown at 10, the tube being of a relatively soft metal, and in the making of tubes, the juncture of boiler tubes and boiler heads, copper is the metal employed. This is a requisite of such rings or bushings, the one end being provided with a flat face and with the other provided with a rounded face, the rounded portion terminating at the inside edge. The tube is held in a die 11 into which it fits with a fairly close fit and it is preferably supported on the inside by a mandrel 12. To prevent backward motion of the tube under treatment I provide jaws 13 which are roughened on the inside face to hold the tube. On the holding die 11 is arranged the cutting die 14 which has an opening 15 which is larger than the tube to an extent to receive the end of the tube when expanded. The plunger 16 is forced into the end of the tube 10 and expands it at 17 in Fig. 2, and the plunger 16 then retreats from the tube and the cutter 18 is forced into the tube and its cutting edge 19 co-operates with the edge 20 of the cutting die to shear longitudinally on the inside across the shoulder

that joins the tube with its expanded portion.

When this takes place the jaws 13 are released to permit the tube to slide back a short distance out of the way and the nose 21 pushes the mandrel back so that the said mandrel forms no obstruction to the easy descent of the cutter. The shoulder 22, which is usually formed by a ring 23, presses on the top ring 24 which has been severed from the tube to form the flat face 25. The ring 23 can also be used as a stripper to slide the ring 24 from the cutter; and the cutter 18 is usually indented slightly as at 26 so that when a cutter retreats it will carry the ring with it and the ring can then be stripped from the cutter by the stripper ring 23. The indentation 26 which is circumferential is very slight, simply enough to hold the ring 24 on the cutter and the inner face of the ring 24 is straightened when the ring is stripped from the cutter.

The completed ring 24 is shown in Fig. 4, one face 25 being flat and the other face 27 being curved, this being the natural curvature of the expanded end of the extension as will be evident from Fig. 2.

After the ring has been made the mandrel 12 and the tube 10 are again advanced so as to present a part of the tube for expanding as shown in Fig. 1, thus providing an intermittent longitudinal movement of the tube and an expanding and shearing of the expanded end when the movement ceases. This provides a practically continuous manufacture of rings from tubing without removing the tube from the machine that performs the successive operations.

In the case of a ring that has both of its edges provided with flat faces as shown at 28 in Fig. 6, the forming die is provided with a square corner as at 31 and when the cutter 18 descends, the shoulder 22 flattens the top face, and the bottom 31 of the recess receives the metal of the ring and flattens the bottom face.

The mandrel is inserted in the tube for the purpose of preventing the collapse of the tube beyond the part that is being expanded by the plunger; and it will also be noted that the rounded end 29, formed when the cut by the cutter is made in conjunction with the

rounded edge 30 of the plunger, serves to permit an easy introduction of the plunger into the end of the tube to force the gradual expansion of the part 17 from the top end of the tube to the bottom of the recess 15.

It will be evident that the parts shown are elementary and the successive operations can be done in any ordinary automatic machine that is now in commercial use for such successive operations, and power-driven machines can be used in the quantity production of rings by this method.

I claim:

1. A method of making rings from a tube which method comprises supporting the tube on the inside and the outside and leaving the end free, then expanding said free end, and then shearing the tube longitudinally at the inner end of the expanded part.

2. A method of making rings from tubing which method comprises the intermittent longitudinal movement of the tube, expanding the tube at its end, and then shearing the tube longitudinally at the juncture of the tube and its expanded part during cessations of the movement.

3. A method of making rings from tubing which comprises an intermittent longitudinal feeding of the tube and an expanding and longitudinal shearing of the expanded part during the intervals between said movements.

4. A method of making rings from tubing which method comprises supporting a tube on the inside, feeding the tube longitudinally to extend the end thereof, expanding said end and supporting said end on the outside, and then shearing the tube longitudinally at the juncture of the expanded part and the tube, the expanding and shearing taking place when the tube movement ceases.

In testimony whereof I affix my signature.
GEORGE E. NEUBERTH.
